RAILROAD SWITCH.
APPLICATION FILED DEC. 30, 1919.

Patented Mar. 22, 1921.

2 SHEETS—SHEET 2.

UNITED STATES PATENT OFFICE.

MIKE BELOFF, OF NEW GLASGOW, NOVA SCOTIA, CANADA.

RAILROAD-SWITCH.

1,372,476.

Specification of Letters Patent. Patented Mar. 22, 1921.

Application filed December 30, 1919. Serial No. 348,478.

To all whom it may concern:

Be it known that I, MIKE BELOFF, a citizen of Russia, residing at New Glasgow, Province of Nova Scotia, and Dominion of Canada, have invented certain new and useful Improvements in Railroad-Switches, of which the following is a specification.

This invention relates to railroad track switches having more particular reference 10 to an automatic means for operating the switch.

The invention has for an object to provide a simple arrangement of parts whereby a train, or single car or locomotive, approaching 15 the switch from a given direction will automatically set the switch in the proper position, the invention being particularly useful at the juncture of sidings with the main line, permitting the train to leave the 20 siding and enter on the main line tracks and restoring the switch to position with the main line tracks open after the train has passed the switch.

For further comprehension of the invention, and of the objects and advantages 25 thereof, reference will be had to the following description and accompanying drawings and to the appended claim in which the various novel features of the invention are 30 more particularly set forth.

Figure 1 of the drawings is a plan view of a railroad track switch having the invention applied thereto.

Fig. 2 is a longitudinal sectional view 35 thereof.

Fig. 3 is a sectional perspective view illustrating particularly the switch locking means.

Fig. 4 is a detail sectional elevation of the 40 train engaging part of the switch operating means.

Fig. 5 is a transverse section on the line 5-5 of Fig. 1.

Fig. 6 shows a detail view of a modified 45 form of the train engaging part of the switch operating means.

In the drawings 1 indicates a pair of track rails and 2 a second pair of track rails leading thereto. For convenience in description I will refer to the track rails 1 as 50 forming part of a main line track, and the

rails 2 as forming part of a siding although it is to be understood that I do not limit myself to any specific application of my improved switch operating means. One of the 55 main track rails 1 has the usual movable switch rail 3 and the opposite one of the siding rails 2 has the usual movable switch rail 4.

Extending transversely under the track 60 at the point where the free ends of the switch rails 3 and 4 are located is a metal plate 5 which may be secured to the fixed rails in any suitable manner. This plate has a pair of apertures formed therein adjacent 65 opposite rails adapted to accommodate the vertically slideable locking bolts 7 which are disposed under the plate and are each provided with a lateral offset such as 8 which limits the upward movement thereof. These 70 bolts are each formed with a vertical slot 9 into which projects a pin 10, fixed in the side walls of respective ones of a pair of recesses 11 and 12 under track which accommodates the device. 75

Each of these bolts 7 has a pin 13 projecting rigidly from its lower end and engaging in a horizontal slot 14 in an operating device controlled by the train, it being understood that the word train is used to 80 designate any single unit of rolling stock, whether a car, locomotive or complete train. The bolt operating means comprises a compound lever member which extends longitudinally in the recess 11 adjacent one of 85 the rails 1. This lever member comprises an arm 15 see Fig. 3 fulcrumed between its ends on a bracket 16 fixed in the bottom of the recess and formed with the slot 14 into which the pin on one of the bolts 7 projects, 90 and having a slot and pin connection 17 at one end see Figs. 1 and 2 with a rock-arm 18 pivoted between its ends to a bracket 19 in the bottom of the recess 11, this latter arm having its opposite end connected by a slot 95 and pin connection 20 with a bell crank lever 21 pivoted to another bracket 19' in the recess and guided by a forked bracket 22 and whose vertical arm 23 is adapted to be engaged and depressed by a suitable part 100 carried by the train. This arm 23 has a rigid transverse offset 25 terminating in a

longitudinal finger 26 provided with a slot 27 in which the pin 13 on the other bolt 7 engages. A spring strap 28 fixed at one end to the track bed as at 29 limits the downward movement of the arm 18 and automatically raises the bolt to locking position. The arm 18 has also a rigid diagonal offset 30 which extends between the siding tracks 2 and is rigidly connected as at 31 with the 10 arm 18 this offset being in the form of a second bell crank pivoted to a post 32 in an offset from the recess and guided by a bracket 33 and adapted to have its vertical arm 34 engaged and depressed by the train. 15 The other end of the first arm 15 has a slot and pin connection 35 with a second rock-arm 36 pivoted between its ends to a bracket 37 in the recess and having a slot and pin connection 38 at its other end with a third bell crank lever 39 pivoted to a post 40 in the recess and whose vertical arm 41 is adapted to be depressed by the train.

The means for shifting the switch rails 3 and 4 when the bolts have been lowered 25 comprises a bar rigidly connecting the switch rails, near the movable ends thereof and having a slot and pin connection 45 with the end of a central offset 46 from a shifter bar 47 pivoted between its ends as at 48, 30 this bar being operated by the following means. Located between the track rails just to the right of the bell crank 21 is a horizontal lever 50 which extends transversely of the rails, being fulcrumed between its 35 ends as at 51. A second lever 52 is disposed between the rails 2 adjacent the bell crank 32 and fulcrumed between its ends as at 53. A third lever 54 extends between the rails 1 adjacent the bell crank 39 and is fulcrumed 40 between its ends as at 55, a fourth lever 56 being disposed just to the left of the last mentioned lever and fulcrumed between its ends as at 57.

A rope or wire 60 connects the end of lever 45 50 nearest the siding with the corresponding end of the shifter bar 47. A second rope 61 connects this end of the shifter bar with the corresponding end of the lever 56 which is in turn connected by a link 62 with the 50 corresponding end of lever 54. The opposite end of the lever 56 is connected by a rope or wire 63 with the opposite end of the shifter bar 47 which is in turn connected by a rope of wire 64 with the end 55 of lever 52 nearest the main rails, the latter rope being guided around a pulley 65.

Upon the ends of each of the levers 50, 52 and 54 opposite to that to which the ropes 60, 64 and link 62 connect is formed a hollow boss 66, in which is slidably mounted a stud 67 having an enlarged head 68 whose upper surface is rounded off as shown in Fig. 4. When the levers are in their normal position this stud rests on the top of 65 a fixed block 69 having an inclined face 70,

the stud being adapted to ride down this face when engaged by a train.

The manner of operation is as follows:— As here shown the device is arranged to maintain the main track rails in operative 70 condition, Fig. 1 of the drawings showing the device in position assumed when a train is passing over the switch from the siding. As the train approaches the switch it first depresses the bell crank 30 which acts 75 through arm 18 to depress the bolts away from the switch rails. The lever 52 is then immediately actuated and swung on its fulcrum in a direction to pull on ropes 64 and shift the bar 47 until the switch rail 4 engages the track rail 1 and the rail 3 is moved to open position, the spring strap 28 immediately throwing the bolts up to locking position. After the train has passed the switch, arm 41 engages 54 which, by thrusting on link 62 pulls on rope 63 and moves the shifter bar to its original position. It is to be noted that as the levers 52 and 54 are shifted the studs 67 ride down the inclined faces 70 of the blocks 69 and thus 80 disengage themselves from the train. It will also be noted that as lever 52 is actuated by the train movement is transmitted to lever 54 to cause it to assume a position with the stud 67 raised and that when the latter is engaged and depressed lever 52 is moved to its original position. Immediately before the last mentioned operation the bell crank 39 is engaged by the train and the bolts 7 lowered from locking position to permit the switch rails to move, the strap 28 immediately returning the bolts to locking position. The operation of the bolts by the bell cranks 32 and 39 is clearly shown by the 85 arrows in Fig. 2.

In the modified form of train engaging part of the switch operating means, the link 62 is connected to a lever 54 pivoted at 55 the free end is adapted to be engaged by a contact element in the train and slides 100 under a segment.

Having thus described my invention what I claim as new and desire to secure by Letters Patent of the United States is as follows:—

In a railway track switch, a pair of vertically movable bolts adapted to lock the switch rails in a selected position, means adapted for automatic operation by a train for first depressing and then raising said 110 bolts, said means including a plurality of rocker arms and a pair of bell crank levers, the latter having upwardly projecting arms adapted to be engaged by a passing train, and means adapted for automatic actuation 120 by a train for shifting the switch rails from one position and then back to said position when the train passes over the switch, said means comprising a shifter bar operatively 125 engaged the switch rails, a plurality of 130

levers extending transversely between the track rails and fulcrumed between their ends to swing horizontally, connections between one end of the lever and the shifter bar, and
5 devices carried by said levers adapted to be engaged by the train to move the latter said devices including vertically movable studs

carried by the opposite faces, and blocks having inclined faces upon which said studs travel as the lever swings to move the studs 10 into and out of the path of the train.

In testimony whereof I have affixed my signature.

MIKE BELOFF.
